CLAIM

The ornamental design for a handle end pivot joint yoke, as shown and described.

DESCRIPTION

FIG. 1 is a top, front and left side perspective view of a handle end pivot joint yoke showing our new design;

FIG. 2 is a front elevational view thereof, the rear elevational view being a mirror image thereof;

FIG. 3 is a left side elevational view thereof with the right side being a mirror image;

FIG. 4 is a top plan view thereof; and,

FIG. 5 is a bottom plan view thereof.

The handle and implement head shown in broken lines in the drawings is for illustrative purposes only and forms no part of the claimed design.

FIG.1

FIG.2

FIG.3

FIG.4
